UNITED STATES PATENT OFFICE.

HENRY A. TOBEY, OF TOLEDO, OHIO.

STEAM-TRAP.

SPECIFICATION forming part of Letters Patent No. 451,533, dated May 5, 1891.

Application filed March 2, 1887. Serial No. 229,395. (No model.)

To all whom it may concern:

Be it known that I, HENRY A. TOBEY, a citizen of the United States, residing at Toledo, in the county of Lucas and State of Ohio, have 5 invented certain new and useful Improvements in Steam-Traps; and I do hereby declare the following to be a full, clear, and exact description of my invention, such as will enable others skilled in the art to which it applies to make and use the same.

In the steam-traps that are in common use in which a closed hollow float is used to actuate the discharge-valve it is established by practice that under pressure such a float 15 eventually fills with water and ceases to be operative. The shell of such float must be of sufficient thickness to resist the pressure to which it is subjected. Consequently the float must be of sufficient size to obtain buoyancy 20 sufficient to support its own weight in addition to that required to raise the discharge-valve against the pressure in the trap, and consequently the case of the trap inclosing such a float must be very large in proportion 25 to the capacity of the trap. In the class of steam-traps in which the difference between the specific gravity of two substances is used to actuate the discharge-valve, there exists the same objection of undue size and weight, 30 for only a portion of the buoyancy obtained by the amount of water displaced is utilized in raising the discharge-valve. The most serious objection found to traps of the classes just mentioned, as well as to that class of 35 steam-traps in which the discharge-valve is actuated by an open-mouthed float rising and falling as it is alternately emptied and filled, is that, unless they are crowded to almost their entire capacity, water collects in them 40 just high enough to lift the float and valve a little, and then escapes as fast as it collects in a thin sheet between the valve and its seat under the full pressure in the trap. The effect is that the continual action of this 45 thin sharp stream soon cuts grooves in the valve and valve-seat and the trap becomes practically worthless. It is established by practice that if a valve of any kind be so far opened that the area of its opening is 50 substantially equal to either the inlet or outlet, as the case may be, it will be but little

worn by the action of a flowing medium, while, on the contrary, wear rapidly increases as this area is proportionally lessened.

The main object of my improved trap is to 55 overcome these objections. In my improved trap the discharge-valve is actuated by an open-mouthed weighted float of peculiar construction, which when emptied rises quickly and closes the valve tightly and when filled 60 sinks rapidly and suddenly throws the valve wide open. The action of the trap is thus rendered intermittent and positive.

In addition to the above-mentioned advantages my improved trap has others of importance, which will be hereinafter described.

In the accompanying drawings, Figure 1 is a side view of my improved trap. Fig. 2 is a central vertical section. Fig. 3 is a perspective view of the valve and bifurcated end of 70 valve-lever, and Fig. 4 is a cross-section just above valve-lever.

Like letters designate corresponding parts in all drawings.

A is a hollow cylindrical casting forming 75 the shell or body of the trap. It is open at the top and has extending from the bottom a projecting portion forming recess B. The interior of casting A is designated as "chamber K," and has an opening into it near the top 80 into which inlet-pipe *t* is secured.

D is a circular-shaped casting forming the lid or cover of casting A, and is securely bolted to flange C of casting A. Casting D has cast integral with it an elevated portion E, the interior of which forms chamber F and central opening *s*, into which is secured pipe *b* leading from the interior of the float to chamber F.

G is a projecting portion of casting D E, 90 containing valve-chamber H, which freely communicates with and is really a part of chamber F and has opening *c* below, into which is secured the discharge-pipe and opening *d* above, through which the valve and 95 valve-seat are introduced and removed, said opening being closed by cap *e*.

P is a casting of suitable shape, forming the base or support of the trap.

J is a hollow float located in chamber K, 100 having a central upward-projecting extension or neck *f* and a central downward-projecting

portion f'' . f is open at the top and forms the mouth or inlet to float J from chamber K . f'' is closed at the bottom.

b is a pipe or tube, which is rigidly fastened 5 into opening s in casting D and extends through the mouth of projection f down through float J to the bottom of projection f , when said float is raised, as shown in drawings.

10 L is a weight or sinker in the shape of a sleeve surrounding projection f , to which it is rigidly secured. The weight of said sinker, in conjunction with that of the shell of the float, should be equal to the greater portion 15 of the buoyancy of the water displaced by said float and sinker. In other words, float J is so loaded that it will barely, when empty, rise with its attached mechanism. Sufficient weight may be provided, as shown, or the shell 20 of the float may be of sufficient thickness to provide the requisite weight.

m is a rod which is secured to the bottom 25 of projection f' of float J , and extends through pipe b into chamber F , the upper end of said rod ending in a link or loop which embraces loosely the shank of screw x , said screw being secured in the end of long arm of lever N , Figs. 2 and 4, said connection being freely movable and having lost motion vertically.

30 Lever N is located in chamber F . Its fulerum is at h . Its long arm, as stated, connects with rod m , and its short arm is bifurcated and engages valve O , Figs. 2, 3, and 4. Valve O rests on valve-seat w and closes the outlet 35 from the trap. The body of said valve has guides, both above and below its connection with lever N , which are in contact with the walls of chamber H , and has shoulders or contact-surfaces k l , Fig. 3, to engage bifurcated 40 end of said lever.

n is a stem connecting the upper and lower 45 portions of the body of valve O , and rests loosely in the crotch formed by the bifurcation of the end of lever N , Figs. 3 and 4. Valve O , therefore, is free to be turned on its vertical axis independently of lever N , and can be readily ground to fit its seat while said lever is in position by removing cap e and placing the end of a suitable tool in slot u in 50 the top of said valve.

In Fig. 3, g is a screw that closes an opening into chamber H opposite valve-seat w , which can be removed to permit the introduction of emery and oil to valve and valve-seat 55 when it is desirable to grind them.

Valve-seat w is secured in and removed from place by means of a suitable tool or wrench introduced from above when valve O and lever N are removed.

60 r is a plug closing an opening into chamber F , through which lever N may be introduced to position and screw x introduced through the loop or link of rod m and secured in the end of the long arm of said lever.

65 h is a bolt which passes through one side of the casting E G , through lever N , forming

the fulerum for said lever, and is secured into the opposite side of said casting, Fig. 4.

The operation is as follows: Chamber K being filled with water to line z z , Fig. 2, 70 float J being fully raised and empty, discharge-valve O being closed, and steam pressure throughout the trap the same, water enters chamber K through inlet-pipe t . Water collects in chamber K and fills the same until its level reaches the top of projection f of float J . The water then begins to flow into the open mouth of projection f down into float J . When sufficient water has collected in float J to overcome the buoyancy—that is, in 80 excess of that required to lift the conjoined weights of the shell of said float and that of sinker L —float J begins to sink and falls to the bottom of chamber K , rapidly filling with water as the top of projection f of said 85 float sinks below the level of the water in chamber K . When float J is resting on the bottom of chamber K , the top of projection f of said float is on a line just above the dotted line z z and the bottom of the body of 90 float J is on a line just above the lower end of pipe b . Float J in its descent engages the end of long arm of lever N by means of rod m , drawing it down, thereby raising discharge-valve O and opening the same, the lost motion 95 of the loop on rod m starting lever N and valve O with a slight impulse or knock. When valve O is opened, pressure in chambers H and F and in pipe b is relieved. Pressure, therefore, in chamber K causes water to flow 100 from said chamber to float J , from float J up through pipe b to chamber F , thence to chamber H , and through open valve out into discharge-pipe c . When water has been discharged from chamber K down to the level 105 of the top of projection f of float J , no more water can enter said float; but the water contained in said float continues discharging. When float J is emptied sufficiently to obtain 110 the buoyancy requisite to lift the weight with which it is loaded, said float begins to rise and continues to rise until the parts of the trap are returned to their original positions, (shown in drawing Fig. 2,) water continuing to be 115 discharged from float J until valve O is closed. When float J is down and water has been discharged from chamber K down to the level of the top of projection f of float J , there is by reason of the small area of upward extension f nearly as much water retained above the body 120 of the float between the level of the top of said extension and the top of the body of said float, as is displaced by the body of said float, projection f , and sinker L . Therefore when float J begins to rise the quantity of water thus 125 retained immediately displaces said float, causing it to rise rapidly to the position shown in the drawings. It will be observed that if sufficient water were not retained above the float when emptied to rapidly lift 130 it to its original position, or if the slow collection of the water of condensation were re-

lied upon to gradually close the discharge-valve by means of a float or other mechanism, the seating of the discharge-valve must be imperfect and the difficulties which my 5 invention is intended to obviate would be encountered.

What I claim as my invention, and desire to secure by Letters Patent, is—

1. A steam-trap comprising in its construction a shell containing a float having an upward extension or neck of less area than its body, and an annular space between such neck and shell, adapted, as described, to contain sufficient water to rapidly fill said float 10 when it begins to sink and to rapidly lift the float when empty to the limit of its upward throw, substantially as shown and described, for the purpose specified.

2. In a steam-trap, the shell A, containing 15 the float J, having upward extension or neck f, and an annular space between the neck and shell, adapted, as described, to contain

sufficient water to rapidly fill said float when it begins to sink and to rapidly lift the float when empty to the limit of its upward throw, 25 in combination with the lower neck or extension f', substantially as shown and described, for the purpose specified.

3. In a steam-trap, the float J, having upward and downward extensions or necks f f' 30 of less area than the body of the float, and adapted, by means of the water contained in the annular spaces surrounding said necks or extensions, to rise rapidly when empty to the limit of its upward travel and to rapidly fall 35 when full to the limit of its downward travel, in combination with the discharge-valve and the valve-actuating mechanism intermediate said float and valve, substantially as shown and described, for the purpose specified.
